UNITED STATES PATENT OFFICE

JOHN WEBER, OF CLEVELAND, OHIO

GAME APPARATUS

Application filed February 14, 1931. Serial No. 515,821.

The game apparatus comprising the present invention is adapted for use in connection with games of chance of the type in which the playing thereof is controlled by preliminary hazards or chances such as is encountered in the playing of dice, backgammon, and other well known games of chance. Toward this end the invention contemplates the provision of a simple apparatus having one or more rotatable indicia carrying elements thereon adapted to be rotated manually or otherwise and to stop in some one of a determined number of positions, the apparatus being so designed that the indicia carrying elements may independently seek any one of the determined positions depending solely upon chance.

The principal object of the present invention is the provision of an apparatus which is comprised of a number of separable parts which are resiliently and releasably held together and which may be readily assembled and disassembled without the necessity of employing tools to aid in the operation of assembly.

A still further object of the invention is to provide a game apparatus, the body portion of which is formed of a resilient material to prevent distortion thereof and which body portion at the same time will prevent damage to a surface upon which it is placed and also, because of its resiliency, will eliminate vibration of the apparatus when in operation.

Yet another object of the invention is to provide a game apparatus which is comprised of a minimum number of parts and which is therefore unlikely to get out of order. Convenience of arrangement of parts, simplicity of construction, and comparative inexpensiveness of manufacture are further desirable features that have been borne in mind in the production and development of the present invention.

With these and other objects in view, which will become more readily apparent as the nature of the invention is better understood, the same consists in the novel construction, combination, and arrangement of parts

shown in the accompanying single sheet of drawings, in which—

Figure 1 is a side elevation of the game apparatus showing the manner in which the various parts are disassembled.

Figure 2 is a side view of the device shown in Figure 1.

Figure 3 is a top plan view of the assembled device.

Figure 4 is a sectional view taken substantially along the line 4—4 of Figure 1.

Figure 5 is a perspective view of a bearing frame forming one of the elements employed in connection with the present game apparatus assembly.

Figure 6 is a sectional view taken transversely through one of the indicia carrying elements employed in connection with the game apparatus, on a plane perpendicular to the axis of said element.

Figure 7 is a sectional view taken substantially along the line 7—7 of Figure 6.

Figure 8 is a side elevation of a closure disc forming a part of the indicia carrying element.

Figure 9 is a sectional view taken substantially along the line 9—9 of Figure 8.

In all of the above described views, like characters of reference are employed to designate like parts throughout.

The device involves in its general organization, a casing 10 generally of rectangular shape and provided with a bottom 12, sides 14, ends 16, and an open top 18. While this casing may be formed in any suitable manner and of any suitable material, it is preferable that the same be formed of a resilient flexible material such as rubber, heavy rubberized fabric, or of a flexible rubber composition. However, irrespective of these details in manufacture, the essential features of the invention are always preserved. The casing is of integral construction, preferably being formed in a mold and the side walls 14 thereof and the end walls 16 are comparatively thick, while the bottom 12 is of comparatively thin construction and is provided with integrally formed legs or supports 20, one at each corner thereof.

The upper portion of the casing is pro-

vided with a rectangular restricted portion 22 providing an upstanding flange surrounding the opening in the open top of the device.

- 5 The open end 18 of the device is adapted to receive therein a bearing frame shown in Figure 5 and designated in its entirety at 24. This bearing frame comprises a rectangular framework 26 which may be stamped from an integral strip of sheet material. The frame is provided with a pair of openings 28 generally of rectangular shape. The longitudinal sides of the openings are provided with downwardly struck flanges 30 into which extend aligned openings 32 centrally of the flanges. The transverse sides of the openings are provided with downwardly struck retaining clips 34, which in the present instance are four in number. These retaining clips are tapered downwardly and are provided with outwardly presented rounded ends 36 which cooperate with internal grooves 38 on the inner side walls 14 of the casing to be received therein to retain the bearing frame in position within the casing. An internal shoulder 40 is formed around the margin of the open side 18 of the casing and the frame member 24 when inserted in position within the casing is adapted to rest upon this shoulder with its upper surface flush with the upper rim of the casing. The side walls 10 are provided with internal notches 42 on opposite sides thereof to accommodate the ends of a bearing shaft 44 which is removably received through the aligned apertures 32 in the flanges 30.

40 A plurality of rotatable indicia carrying elements are shown at 46. Each member is in the form of a wheel having a rim 48, the outer periphery of which is uniformly polygonal in shape. In the present instance the rim is shown as being provided with six peripheral faces 50, each of which has formed thereon in any suitable manner as for example by molding, a number of indicia designated at 52. A pair of hub members in the form of shallow discs, shown in Figure 8, are designated at 54. These hub members are provided with central hubs 56 through which the shaft 44 extends, and from each hub there extends a radial portion 58 provided with an inwardly offset peripheral flange 60. Each rim 48 is made of resilient material and is provided with a pair of spaced internal grooves 62 adapted to receive the offset flange 60 of the hub 58. The grooves 62 are so spaced from the edge of the rim that when the rim is positioned on a hub member the side of the rim will lie substantially flush with the 55 radial portion 58 of the hub. Obviously, each rim is operatively supported by two spaced hubs.

The interior wall of the rim 46 of each indicia carrying element is of undulatory form, being provided with a number of cavities 65

ties 64 and crests 66 radially positioned around the rim. The number of cavities provided on the rim corresponds to the number of indicia on the rim, and the center of each cavity is positioned directly on the inside of the center of an indicia formed on the outside of the rim. All of the cavities are of equal depth and size, and housed within each of the indicia carrying elements are a plurality of weighted balls 68 identical in size and weight. While any desirable number of these balls may be employed, advantageous results have been obtained where three are provided. However, regardless of the number of balls employed, the principles of the invention are not altered. The indicia carrying elements 46 are positioned within the frame 24, one within each opening 28, in such a manner that they are supported centrally upon the shaft 44 which extends completely across the frame transversely. The size of the rims of the indicia carrying elements is preferably such that a minimum amount of space exists between the outer edge of the rim and the side of the housing in order that foreign substances such as dirt or the like will not collect within the housing.

In assembling the device, the indicia carrying elements are positioned within the openings 28 of the frame 24 and the shaft, which is in the form of a pintle pin is inserted through the aligned apertures 32 in the flanges 30, and in the discs 54 so that each indicia carrying element is rotatably mounted within its respective opening with a portion thereof projecting upwardly above the top of the frame. The frame may then be inserted in proper position within the housing by grasping the ends of the housing between the thumb and forefinger and springing the open top of the housing into the distorted position shown in Figure 1 to permit the downwardly extending retaining members 34 to be inserted within the open top. The rounded projections 36 will snap into position within the internal grooves 38 in the side walls 14 and the device is thus assembled. In order to operate the device, a player may position his forefinger and his index finger simultaneously and respectively against the projecting part of the indicia carrying element. By a sudden rearward movement of the hand, the indicia carrying elements may be flicked, so to speak, into rotational movement, the casing resting on a supporting surface and being held against slipping movement by virtue of the relatively high coefficient of friction afforded by the rubber material of which the casing is made. The balls 68, which are positioned for freedom of movement within the indicia carrying elements, will, as these elements come to rest, seek any one of the number of cavities 64 formed on the inner wall of the rim on which to rest their weight and when the de- 125

vice finally comes to rest, these balls resting on the cavity will so weight the device that an indicia face will present itself horizontally above the casing and there will be no possibility of an indeterminate reading of the indicia face.

The invention is not to be limited to the exact arrangement of parts shown in the accompanying sheet of drawings or described in this specification, as various changes in the details of construction thereof may be resorted to without departing from the spirit of the invention. For example, the frame 24 which is provided with the resilient depending prongs 34 may be employed in connection with a nonresilient casing formed of a suitable composition such as bakelite or the like, or which may be formed of metal. The resiliency of the spring members 34 will serve to retain the frame in position within the nonresilient casing and upon distortion of the members 34 the frame may easily be removed from the casing. For further example, in the drawings, for the purpose of illustration, the indicia are of the type ordinarily employed in dice, and represent numbers ranging from one to six, inclusive, but it is to be understood that various colors, and designs, as for example playing card suits, such as hearts, spades, or the like, or in fact any desired indicia may replace the spots that are herein illustrated. Furthermore, the number of faces that may be employed in the indicia carrying elements may be varied while the number of weighted units within the indicia carrying elements may likewise be varied. These features of the invention are immaterial and may be altered so long as the spirit of the invention is not destroyed. Only insofar as the invention has been particularly pointed out, is the same to be limited.

Having thus described my invention, what I claim as new and desire to secure by Letters Patent of the United States, is—

1. In a game apparatus, a resilient distortable casing, a bearing frame having a rotatable indicia carrying element therein, said frame being received within said casing and held therein solely by the resiliency of the distortable casing.

2. In a game apparatus of the class described, a distortable casing, a bearing frame having a rotatable indicia carrying element mounted therein, cooperating means on said frame and casing for normally retaining said frame within said casing, and operable by distortion of the casing for releasing said retaining means.

3. A game apparatus comprising a resilient casing having an inner wall provided with a recess, a bearing frame, a rotatable indicia carrying element mounted within said frame, a projection on said frame receivable in said recess for retaining the frame in position

within the casing, said casing being manually distortable to remove said projection from said recess to permit withdrawal of the frame from the casing.

4. In a game apparatus, a resilient distortable casing, a bearing frame, a rotatable indicia carrying element mounted in said frame, inter-engaging means on said frame and casing for releasably holding said frame in position within the casing, said inter-engaging means being adapted to be rendered inoperative upon distortion of said casing.

5. In a game apparatus, a resilient distortable casing, a frame receivable within said casing, said frame being held in position by frictional engagement with the casing, said casing being manually distortable to release said frame.

6. A game apparatus comprising an integral casing formed of a yieldable distortable material and having an open top, a game unit frictionally receivable in said open top, said open top being distortable to release said game unit upon contraction of the lower portion of said casing.

7. A game apparatus comprising a casing formed of yieldable resilient material, said casing having an open end, a frame positioned within said open end and extending thereacross, there being an opening in said frame, a shaft extending across the opening, a rotatable indicia carrying element mounted within the opening for rotation upon said shaft, said frame being held within said opening by contraction of the casing on the same, and said casing being distortable to release said frame.

8. A game apparatus comprising a casing formed of yieldable resilient material, said casing having an open end, a frame positioned within said open end and extending thereacross, there being an opening in said frame, a shaft extending across the opening, and a rotatable indicia carrying element mounted within the opening for rotation upon said shaft, said frame being held within said opening by contraction of the casing on the same, said casing having a plurality of supporting elements formed thereon adapted to be engaged manually and urged toward each other to distort said casing and release said frame.

9. In a game apparatus, a yieldable resilient casing having an opening therein, a frame positioned within said opening and held therein by contraction of said casing upon said frame, a plurality of openings in said frame, a shaft extending through said frame and bridging said openings, a plurality of rotatable indicia carrying elements mounted upon said shaft and positioned one within each opening and projecting above the top of the casing for manipulation thereof, a downwardly extending retaining element on said frame having a projection thereon, a recess in the inner wall of said casing

adapted to receive said projection to retain said frame in position within the casing, said casing being distortable to remove said projection from said opening and permit removal of said frame.

10. In a game apparatus, a yieldable resilient casing having an opening therein, a frame positioned within said opening, a plurality of openings in said frame, a shaft extending through said frame and bridging said openings, a plurality of rotatable indicia carrying elements mounted upon said shaft and positioned one within each opening and projecting above the top of the casing for manipulation thereof, a downwardly extending retaining element on said frame having a projection thereon, a recess in the inner wall of said casing adapted to receive said projection to retain said frame in position within the casing, said casing being distortable to remove said projection from said means and permit removal of said frame.

11. In a game apparatus, a casing element, a frame element receivable within said casing, inter-engaging means on said frame and casing for releasably holding said frame in position within the casing, said inter-engaging means being adapted to be rendered inoperative upon distortion of one of said elements.

12. In a game apparatus, a rotatable indicia carrying element comprising a resilient rim having an internal groove therein, and a hub carrying disc having a radial flange receivable in said groove.

13. In a game apparatus, a rotatable indicia carrying element comprising a resilient rim having a pair of internal grooves, and a hub carrying disc having a radial flange receivable in each groove to provide a closed casing, and a weighted element within the casing.

14. In a game apparatus, a rotatable indicia carrying element comprising a resilient rim having a pair of internal grooves, and having an undulatory inner surface, a pair of discs provided with hubs, said discs having radial flanges, the flange of each disc being frictionally held within respective grooves.

15. In a game apparatus, a rotatable indicia carrying element comprising a resilient rim, a radial disc frictionally held within said rim.

55. In testimony whereof I affix my signature.

JOHN WEBER.
